US00D781416S

(12) **United States Design Patent** (10) **Patent No.:** **US D781,416 S**
(45) **Date of Patent:** **** Mar. 14, 2017**

(54) **MEDICAL DEVICE HANDLE**

(71) Applicant: **Custom Medical Applications, Inc.**,
Johnstown, NY (US)

4,191,186 A 3/1980 Keeler
4,304,231 A 12/1981 Bodicky et al.
4,362,156 A 12/1982 Feller, Jr. et al.
5,071,412 A * 12/1991 Noda A61M 5/007
604/176

(72) Inventors: **N. Sandor Racz**, Farmers Branch, TX
(US); **Gabor J. Racz**, Farmers Branch,
TX (US)

(Continued)

(73) Assignee: **Custom Medical Applications, Inc.**,
Johnstown, NY (US)
